UNITED STATES PATENT OFFICE

WILLIAM H. BLAKE, OF WATERBURY, CONNECTICUT.

DESIGN FOR AN UMBRELLA TIP-CUP.

Specification forming part of Design No. **11,356**, dated August 19, 1879; application filed June 23, 1879.
[Term of patent 3½ years.]

To all whom it may concern:

Be it known that I, WM. H. BLAKE, of Waterbury, in the county of New Haven and State of Connecticut, have invented a new Design for Umbrella Tip-Cups; and I do hereby declare the following, when taken in connection with the accompanying drawings and the letters of reference marked thereon, to be a full, clear, and exact description of the same, and which said drawings constitute part of this specification, and represent, in—

Figure 1, a side view of the cup on its sleeve; Fig. 2, the cup detached.

This invention relates to a design for the cup-shaped slide which is applied to the staff of umbrellas to set over the tips of the ribs when closed, so as to secure them in the closed position, and known as "tip-cups;" and the invention consists in the shape of the cup, as shown in the accompanying illustration.

A is the sleeve on which the cup B slides. The cup in vertical section consists of two beads, the one, *a*, forming the larger part or body, and the other, *b*, forming the head, and the contracted part *c*, between the two beads, the neck, this large bead *a*, smaller bead *b*, and neck *c* constituting the peculiar features of this invention.

I claim—

The design for umbrella tip-cup, consisting of the large bead *a*, smaller bead *b*, and contracted neck *c* between, as shown in the accompanying illustration.

WM. H. BLAKE.
